MANIFOLDING

Carl Heim, Jersey City, N. J., assignor to Auto-graphic Register Company, Hoboken, N. J., a corporation of New Jersey

Application April 7, 1938, Serial No. 200,609

6 Claims. (Cl. 282—12)

This invention relates to manifolding, and, more particularly, to the method of making continuous piles, including interleaved record and transfer strips, and to a novel form of transfer strip.

5 Heretofore, it was proposed to zigzag fold the record and carbon strips and then bring the folded strips together so that the carbon strips are interleaved with the record strips and the folds on the two kinds of strips are nested one within the other.

10 It was also proposed, heretofore, to provide the line of severance between the record strip and the transfer strip in such a way that when 15 a set of strips is severed from the pile of continuous strips along the fold lines which are usually weakened, a tab will be provided on one end of the carbon while a notch, from which a similar tab was removed, is provided on the other end of the carbon. The tab portion, in 20 many instances, has been left attached to the adjacent form by a tit or narrow band of material so that the tab portion would fold with the adjacent form to which it is attached. In many 25 cases, it is desirable to have the tab in the carbon completely cut from the adjacent form, but, in interleaving and refolding such carbon strips with the record strips, it was difficult to keep the tabs from folding on themselves, so that they 30 would not project beyond the edges of the record strips as they are intended.

The present invention has solved this problem by the making of a novel and improved form of carbon strip supply for use in making up interleaved continuous record and carbon strips. According to the present invention, instead of attempting to fold the tab portion of the carbon strip, it is allowed to remain unfolded, the carbon strip being folded on a weakened fold line, a continuation of which would go through the tab.

40 I have found that with the tab on the carbon strip unfolded and uncreased, when it is interleaved between the record strips and the latter are folded on their weakened fold lines, the tab becomes folded and is prevented by the interposed strip material from folding directly on itself. The result is that, when the strips are torn along the weakened fold lines, the tab will always project beyond the record strips and not lie folded on the carbon sheet to which it is attached so as to be within the pile out of reach.

45 It will thus be seen that the present invention contemplates creasing the carbon strip in two steps, the strip being creased, except for the tab portion, during its manufacture, and having the

tab portion creased during the operation of interleaving the carbon strip with the record strip.

Other features and advantages will hereinafter appear.

In the accompanying drawing which illustrates the present invention—

Fig. 1 is a perspective view of a zigzag folded carbon strip made according to the present invention.

Fig. 2 is a perspective view, showing the carbon and record strips in the act of being brought together and zigzag folded into a single pile.

Fig. 3 is a perspective view of a pile of manifolding strips, including the record and carbon strips, showing the tab on the carbon projecting beyond the record strips.

Fig. 4 is a sectional view, showing the position of the tab on the carbon strip during the operation of collating the record and carbon strips.

Fig. 5 is a sectional view, showing the position of the pack in the folded pile of record and transfer strips.

As shown in Fig. 3, the manifolding pack of the present invention comprises a plurality of record strips 10 interleaved with one or more transfer strips 11, and folded zigzag along weakened fold lines 12 to form a zigzag folded pack 13 from which the leading or top end of the pile may be taken and introduced into a typewriting machine.

As previously proposed, the carbon strip is so arranged as to have a tab 14 projecting beyond the adjacent edges 15 of the record strips at one end of the pile of sheets severed from the pack 13, and a notch corresponding in shape to the tab at the other end of the pile of sheets inwardly removed from the adjacent edge of the record sheets, so that, when the carbon tabs 14 are grasped by the fingers of one hand and the record sheets are grasped by the fingers of the other hand over the notched portion of the carbon sheet, pulling of the hands apart will strip all of the carbons from all of the records. The records and carbons are folded at sheet-length intervals along transverse lines of weakness 16, and the tab on one sheet length of the transfer strip is taken from the adjacent end of the next sheet length of the transfer strip.

In most cases, the tab 14 is outlined by several incisions, or other weakening lines such as perforations, so that the tab remains structurally united to the sheet length of the carbon strip within which it lies, there being ties, or even a single tit, between the margins of the tab and the adjacent margin of the sheet from which it is formed.

In this situation, when the carbon strip is taken from a zigzag folded pile to be interleaved with similarly folded record strips, the tab also unfolds and has no opportunity of remaining folded upon itself as the carbon goes between the record strips and the pile is refolded. Therefore, the tab will always project beyond the edges of the record strips when a set of sheets is torn off from the pile along the fold line.

10 In many instances, it is desirable to have the tab formed by an incision so that it is entirely free from the sheet length from which it was formed, to reduce the chance of the tab being inadvertently torn off in the severing operation.

15 In this case, great difficulty has been encountered in keeping the tab from being folded over on itself at the time when, as in Fig. 2, the record strips 10 and carbon strips 11 are being collated and refolded into a single pack.

20 According to the present invention, this difficulty is obviated by so preparing and forming the tab and the resulting notch that the tab is not folded in a zigzag folded pile of carbon strips. As shown in Fig. 1, the tab 14 is formed 25 by an incision intersecting the weakening line 16 in the carbon strip, and so folding the carbon strip that the tab 14 is not folded but lies in the plane of the sheet length to which it is attached. Preferably, although not necessarily, the weakening line 16 does not extend across the tab, and hence the tab remains an uninterrupted continuous part of the sheet length to which it belongs.

25 The carbon pack, illustrated in Fig. 1, may be made up and sold as such to be collated with record strips similarly divided into sheet lengths. When the carbon strip is, as diagrammatically illustrated in Fig. 2, collated with zigzag folded record strips, the uncreased tabs 14 will lie in the 30 pile substantially as shown in Fig. 4, projecting straight into the space between the next sheet lengths of the upper and lower record strips 10 which have their creases 17 in register with the 35 creases 18 in the carbon strip. Then, when the pile of strips is folded, the base of the tab will 40 always be folded to correspond with the creases 17 in the record strips and the tab will occupy the position shown in Fig. 5, having returned to the notch 19 from which it was cut originally and 45 being prevented by the interposed record strip 10 from folding directly upon itself, where it would not be in position to be grasped when the 50 set of written forms is severed from the pile.

55 It will thus be seen that the carbon strip is folded in two separate operations, one operation folding the main portion of the strip and being done during the manufacture of the pack of continuous carbon paper, and the other part, i. e., the tab, being folded during the operation 60 of assembling the record and carbon strips. The carbon strip material being rather thin and not too stiff, the tab 14 is folded by merely being confined between the folds of the upper and lower record strips, which, having previously been 65 creased, automatically assume refolded condition. Applying light pressure, as by the hands, to the refolded pack, will definitely cause the tab to be creased.

It should be understood that within the scope

of this invention the tab may be of any desired shape and it may be located either at the top of the sheet length or at the bottom and to one side of the center or directly on the center as shown, without departing from the present invention.

5 Variations and modifications may be made within the scope of this invention and portions of the improvements may be used without others.

10 I claim:

1. As a new article of manufacture, a strip of carbon paper divided into sheet lengths by transverse lines of weakness and folded zigzag on said transverse lines of weakness to form a pack, said carbon strip having at each line of weakness incisions intersecting the line of weakness and forming a tab on one sheet length cut from the adjacent sheet length in the strip, said tab being left unfolded and lying in the plane of the sheet length to which it is attached. 20

2. As a new article of manufacture, a strip of carbon paper having at each sheet-length interval a transverse weakened fold line interrupted between its ends by an incision joining said weakened fold line at the interrupted portions and extending into the adjacent sheet length to form a tab, said strip being zigzag folded on said weakened fold lines leaving the tab projecting beyond the ends of the zigzag folded pack thus formed. 25

3. A zigzag folded pack of transfer paper having tab portions projecting beyond the folds of the paper and beyond the ends of the pack. 30

4. The method of making manifolding packs which includes the steps of weakening and zig-zag folding at sheet-length intervals a continuous transfer strip and cutting out tabs on the fold lines, said tabs being left not folded, interleaving said transfer strip between record strips similarly weakened and folded, with the folds of record and transfer strips one within the other, and then folding said record and transfer strips together and simultaneously folding the tab to cause the same to lie in the space from which it was cut out and in interleaved relation with both record strips. 35

5. As a new article of manufacture, a strip of carbon paper divided into sheet-lengths by interrupted transverse lines of weakness and having at each interruption an incision forming a tab on one sheet-length cut from the adjacent sheet-length in the strip, said strip being folded zigzag on said transverse lines of weakness to form a pack, the tab not being folded but projecting from the edge of the pack as a continuation of the sheet-length to which it is attached. 50

6. A pack of transfer paper comprising, a zig-zag folded strip of transfer paper, having unfolded tab portions projecting beyond an edge thereof, said transfer pack being adapted to be 60 drawn out flat and folded with similarly folded record strips, said tabs as the transfer strip is interleaved and folded with the record strips being disposed between adjacent record strips and folded across the base portions thereof to lie 65 within the pack of folded transfer and record strips.

CARL HEIM.
